ARTIFICIAL LIMB JOINT CONSTRUCTION

William J. Didier, Racine, Wis.

Application November 25, 1933, Serial No. 699,697

8 Claims.

(Cl. 3-2)

This invention relates to a joint for an artificial limb and to an artificial limb construction, and is particularly directed to a construction for amputations above the knee.

5 Objects of this invention are to provide an artificial limb joint, the construction of which has extreme strength, which resists both direct pressure, as when the weight of the user is suddenly thrown upon the artificial limb, and which resists side pressure, or unevenly applied pressure, without subjecting any part thereof to excessive strain, and which has widely spaced ball bearings that transmit all pressure from one portion of the limb to the other.

10 15 Further objects are to provide a joint for an artificial limb which runs or turns entirely upon widely spaced ball bearings, and which swings or rocks with the utmost ease.

Further objects are to provide novel construction for returning the limb and for checking it at the proper place, to provide a single spring which serves both as the return means and as the check, which is silent and positive in operation, and which does not stretch in use, thereby 20 25 maintaining a fixed position at which the limb is checked irrespective of the length of time the joint is in use.

A further object is to provide an artificial limb joint of such construction that the upper portion 30 35 of the joint is rigidly and firmly secured to the upper leg member without the use of any auxiliary screws or other fastening means.

An embodiment of the invention is shown in the accompanying drawings, in which:—

35 Figure 1 is a vertical sectional view through an artificial limb, with parts broken away, which shows the joint in transverse section as actually applied.

Figure 2 is an enlarged sectional view on the 40 line 2—2 of Figure 1.

Figure 3 is an enlarged transverse section through the joint removed from the limb.

Figure 4 is a sectional view on the line 4—4 of Figure 3.

45 Figure 5 is a view of the spring rest removed from the rest of the apparatus.

Referring to the drawings, it will be seen that the artificial limb comprises an upper portion 1, which may be called the thigh portion, and a 50 lower portion 2, which may be called the lower leg portion. The upper member or thigh portion is provided with a rounded lower bottom part 3 which projects downwardly, as may be seen from Figures 1 and 2, into the lower leg 55 portion 2, although clearing such leg portion, that is to say, remaining out of contact therewith in all positions of swinging of the lower leg portion.

The joint comprises a body portion formed of 60 a composite sleeve, the sleeve itself being com-

posed of two members 4 and 5, see particularly Figures 2 and 3, one of which, for example the member 5, is provided with a threaded shank 6 of reduced diameter which fits into an internally threaded portion 7 of the member 4.

Between these members a spring carrying rest 8 is positioned, see Figures 1, 2 and 3. This spring rest is shown to an enlarged scale in Figure 5. This spring carrying rest is bored out, as indicated at 9 in Figures 1 and 5, to receive 10 the cylindrical members 4 and 5 forming the body or main sleeve, so that these members fit directly beneath and contact with the bored out or arched portion 9 of the spring support 8.

In addition, the member 8 is provided with a 15 tongue or central web 10 which is apertured and through which the extension or shank 6 of the member 5 passes, so that this web 10 or central tongue is clamped tightly between the members 4 and 5 when such members are screwed together.

In addition to this, the upper leg member 1 is provided with cylindrical recesses or bored out parts 11 and 12 which terminate in shoulders against which the shouldered heads 13 and 14 25 30 respectively engage.

It is to be noted from reference to Figures 2, 3 and 4 that the headed or shouldered members 13 and 14 are each provided with spanner wrench receiving slots 12'.

In addition to this, the cylindrical body portions of the members 4 and 5 fit accurately within the correspondingly bored out portions of the upper leg member 1, as shown in Figure 2, so that when the two members 4 and 5 are tightly 35 40 45 locked together and clamped against the central web 10 of the member 8, they also tightly bind and lock themselves to the upper leg member without requiring the use of any screws or auxiliary fastening means whatsoever.

It is to be noted also that the member 10 is securely anchored in place by this arrangement, also without the use of auxiliary fastening means, such as screws, etc. From reference to Figure 1, it is clear that the upper leg member 45 is provided with spaced shoulders 15 and 16 upon which the end portions of the member 8 rest when its central web 10 is clamped between the members 4 and 5. Thus each of these three parts 4, 5, and 8 is securely locked in a rigid 50 55 60 65 70 75 80 85 90 95 100 and firm manner to the upper leg portion 1.

A pair of ball bearings each provided with an outer race 17 and an inner race 18 are provided for opposite ends of the joint. The outer races 18 fit securely within the socketed enlargements 55 60 65 70 75 80 85 90 95 100 13 and 14 at the ends of the members 4 and 5, the balls of course being positioned between these ball races. The inner ball races are in engagement with the ends of an inner sleeve or spacing sleeve 19. This sleeve passes through 60 65 70 75 80 85 90 95 100

the members 4 and 5 and clearance is preferably provided between such members.

In addition to this, a bolt 20 extends through the sleeve 19 and has clearance between itself and the sleeve so that there is no wear whatsoever and no engagement between the bolt and the sleeve, the weight or pressure being transmitted solely through the ball bearings. The inner races 18 are thus held spaced from the members 4 and 5 and frictionally and mechanically free thereof.

Supporting arms 21 and 22 are secured to the lower leg member 2 and are apertured to receive the bolt 20, such bolt or elongated screw being headed at one end, as indicated at 23 in Figure 2, and being threaded at the other end, as indicated at 24.

The members 21 and 22 are provided with disk-like rounded upper ends 25 and 26 which fit within the recesses 11 and 12 formed in the upper leg member 1 and which are out of contact with the upper leg portion.

The member 25 is screw threaded upon the threaded portion 24 of the bolt and is locked thereto by means of a lock nut 27. This lock nut is preferably provided with a transverse slot, as indicated, so as to receive a spanner wrench and allow it to be locked tightly to thereby tightly lock the bolt against unscrewing.

30 The bolt 20 is drawn up tight, as shown in Figures 2 and 3, thereby clamping the inner races 18 tightly against the ends of the spacing sleeve 19 and tightly against the inner bosses formed on the disks 25 and 26 of the members 21 and 22, as shown in Figure 2.

When the lower leg member is rocked with reference to the upper leg member, the members 21 and 22, the bolt 20, and the sleeve 19, together with the inner races 18, rock as a unit and the outer races 17 are held by the members 13 and 14. Thus the entire weight of the body is transmitted solely through the agency of the ball bearings and a very free unhampered rocking motion is thus provided.

45 Means are provided for returning the lower leg to its original or extended position, as shown in full lines in Figure 1, after the lower leg has been rocked rearwardly for example to the dotted line position as shown in Figure 1. This means also in the present invention constitutes at the same time a check for checking the forward swinging motion of the leg and to stop it at a predetermined fixed point which is positive and which is maintained throughout the long period of operation of the device.

60 This means comprises a flat leaf spring 28 which is secured to the upper side of the spring support or member 8 and clamped thereto by means of a plate 29. This plate and the member 8 are each curved towards the rear and it will be seen that the plate 29 is provided with a downward extension 30 provided with an outwardly turned lip 31. This plate is held locked to the member 8 by means of screws 32 so as to tightly and securely clamp the spring 28 in place. The lower end of the spring is clamped to an anchored block 33 by means of a plate 34, such plate being held in place by screws 35, such screws also passing through the lower leg member.

65 It is preferable to provide a felt or other padding 36 for the upper leg member in front of the spring 28 and to provide a felt or other packing 37 on the inner side of the lower leg member 2 against which the spring may bear.

This also cushions the spring and prevents any noise during the operation of the spring.

In using the device the user merely places his weight upon the artificial limb while the parts are in their locked or full line forward position, as shown in Figure 1. After placing the other foot on the ground, he thereafter moves his leg forward allowing the lower leg to pivot about the joint, as indicated in dotted lines in Figure 1. Upon slightly raising the foot of this leg from the ground, the lower leg swings forwardly due to the action of the spring 28, such spring acting, as previously stated, as a combined restoring means and check. Obviously when the spring is in the dotted line position shown in Figure 1, it will exert a force tending to restore it and will correspondingly rock the lower leg forwardly. However, after the lower leg has rocked forwardly, further forward motion of the lower leg is prevented due to the fact that the spring then becomes taut and arrests further forward motion of the lower leg.

25 The spring does not stretch and may be made as wide as needed. It very readily and easily furnishes sufficient restoring power and also furnishes at the same time a positive non-elongating checking means for stopping the forward motion of the lower limb at a predetermined point.

30 It will be seen that a very simple and serviceable type of artificial limb construction and joint therefor has been provided by this invention which has a minimum number of easily produced and sturdy parts. Also it will be seen that there are no projecting portions which might cause annoyance to the user or which might detract from the appearance of the artificial limb. In addition to this, the limb is remarkably strong and will stand a suddenly applied large weight or pressure and cannot be distorted, the ball bearings being provided to insure ease of operation and also being widely spaced to prevent warping or binding of the parts. The utmost lateral rigidity is provided by this construction, while at the same time securing the maximum freedom and ease of operation.

35 In addition to this, the parts are so made that they all readily lock together as hereinbefore described in a simple and reliable manner without the use of any auxiliary screws, bolts, or other fastening means.

40 This device has been actually used even for double amputations above the knee. It is obvious that the maximum security and the maximum positiveness of operation is required where this severe condition has to be met. Even under these conditions the device functions perfectly in actual practice.

45 Although this invention has been described in considerable detail, it is to be understood that such description is intended as illustrative rather than limiting, as the invention may be variously embodied and is to be interpreted as claimed.

I claim:

1. An artificial limb joint construction comprising an upper member and a lower member pivotally joined together, a spring rest carried by said upper member and having a rearwardly projecting portion, and a leaf spring secured adjacent its upper portion to said spring rest and extending over the rearwardly projecting portion of said spring rest and attached adjacent the lower portion of said spring to said lower member, whereby said spring urges said lower member towards a forward position, and

arrests the forward swinging motion of said lower member at a predetermined point with respect to said upper member.

2. An artificial limb joint construction comprising an upper member and a lower member pivotally joined together, a spring rest carried by said upper member and having a rearwardly projecting portion, a leaf spring secured adjacent its upper portion to said spring rest and extending over the rearwardly projecting portion of said spring rest and attached adjacent the lower portion of said spring to said lower member, whereby said spring urges said lower member towards a forward position and arrests the forward swinging motion of said lower member at a predetermined point with respect to said upper member, and cushioning means for said spring.

3. An artificial limb joint construction comprising an upper member and a lower member pivotally joined together, a spring rest carried by said upper member and having a rearwardly projecting portion, a leaf spring secured adjacent its upper portion to said spring rest and extending over the rearwardly projecting portion of said spring rest and attached adjacent the lower portion of said spring to said lower member, whereby said spring urges said lower member towards a forward position and arrests the forward swinging motion of said lower member at a predetermined point with respect to said upper member, and cushioning means for said spring, said cushioning means being carried jointly by said upper and lower members.

35 4. An artificial limb joint construction comprising an upper member and a lower member pivotally joined together, a spring rest carried by said upper member and having a rearwardly projecting portion, a leaf spring secured adjacent its upper portion to said spring rest and extending over the rearwardly projecting portion of said spring rest and attached adjacent the lower portion of said spring to said lower member, whereby said spring urges said lower member towards a forward position and arrests the forward swinging motion of said lower member at a predetermined point with respect to said upper member, and a plate secured to said spring rest and having a downwardly extending tongue located rearwardly of said spring.

50 5. An artificial limb joint construction comprising an upper member and a lower member, a spring rest carried by said upper member and having a downwardly extending apertured web, a main sleeve formed of two parts, screwed together and passing through the aperture of said web and having inner shoulders gripping said web, said sleeve fitting within the lower portion of said upper member and having outer shoulders clamping the lower portion of said upper member between them, ball bearings having outer races carried adjacent the ends of said main sleeve and having inner races, said lower member having a pair of spaced arms on opposite sides of said inner races, a spacing sleeve between said inner races, a bolt passing through said arms and spacing sleeve and clamping said arms to said inner races, and a spring secured to and carried by said spring rest and having its lower end secured to said lower member of said artificial limb.

6. An artificial leg joint construction com-

prising an upper leg member and a lower leg member, a main body portion locked to said upper leg member and comprising a composite main sleeve formed of two opposed parts locked together by screw threaded interengaging portions, an inner sleeve located within said main sleeve, anti-friction bearings located adjacent opposite ends of said main sleeve and having inner and outer races, said outer races being carried by said main sleeve, side members carried by said lower leg portion, and a bolt extending through said inner sleeve and said side members and locking said inner races rigidly between the ends of said inner sleeve and the corresponding side members, the parts of said main sleeve having shoulders thereon and said upper leg member having its lower portion tightly gripped between said shoulders when the two parts of said main sleeve are locked together by said interengaging screw threaded portions, said bolt exerting no clamping pressure on said upper leg member.

7. An artificial leg joint construction comprising an upper leg member and a lower leg member, a main body portion locked to said upper leg member and comprising a composite main sleeve formed of two opposed parts locked together by screw threaded interengaging portions, an inner sleeve located within said main sleeve, anti-friction bearings located adjacent opposite ends of said main sleeve and having inner and outer races, said outer races being carried by said main sleeve, side members carried by said lower leg portion, a bolt extending through said inner sleeve and said side members and locking said inner races rigidly between the ends of said inner sleeve and the corresponding side members, the parts of said main sleeve having shoulders thereon and said upper leg member having its lower portion tightly gripped between said shoulders when the two parts of said main sleeve are locked together by said interengaging screw threaded portions, said bolt having a head at one end engaging one side member and being threaded into the other side member, and a locking nut screwed on said bolt and locking said bolt against unscrewing, said bolt exerting no clamping pressure on said upper leg member.

8. An artificial leg joint construction comprising upper and lower leg members, a main body portion locked to one of said members and comprising a composite main sleeve formed of two opposed sleeves locked together by screw threaded interengaging portions, an inner sleeve located within said main sleeve, ball bearings located adjacent opposite ends of said main sleeve and having inner and outer races, said outer races being carried by the end portions of said main sleeve, side members carried by the other leg portion, and a bolt extending through said inner sleeve and engaging the side members, said bolt locking the inner races tightly between opposite ends of said inner sleeve and the corresponding side members, said main sleeve having headed ends clamping a portion of said first mentioned leg member between such headed portions when the two members of said main sleeve are screwed together, said main sleeve having means associated therewith to limit the clamping pressure imposed on the first mentioned leg member by the headed ends of said main sleeve.

WILLIAM J. DIDIER.
